UNITED STATES PATENT OFFICE

172,853

SUGAR BOWL OR THE LIKE

John O. Van Koert, New York, N. Y., assignor to Towle Manufacturing Company, Newburyport,
Mass., a corporation of Massachusetts

Application May 13, 1954, Serial No. 30,453

Term of patent 14 years

(Cl. D44—15)

To all whom it may concern:

Be it known that I, John O. Van Koert, a citizen of the United States of America, residing at New York, county of New York, New York, have invented a new, original, and ornamental Design for a Sugar Bowl or the like, of which the following is a specification, reference being had to the accompanying drawings, forming a part thereof.

This application is a continuation-in-part of my application Serial No. D. 24,981, filed May 12, 1953, and now abandoned.

Fig. 1 is a front elevational view of a sugar bowl or the like, showing my new design; and
Fig. 2 is a side elevational view thereof.

I claim:

The ornamental design for a sugar bowl or the like, substantially as shown.
